(57) **CLAIM**

The ornamental design for an earphone protective sleeve, as shown and described.

DESCRIPTION

FIG. 1 is a top, front and right side perspective view of an earphone protective sleeve, showing my new design; FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a top, front and right side perspective view of the earphone protective sleeve in a configuration of use.

The broken lines in the drawings depict portions of the earphone protective sleeve that form no part of the claimed design.
